Primary Examiner — Sandra Snapp*Assistant Examiner* — Holly E Thurman(74) *Attorney, Agent, or Firm* — Burr & Brown, PLLC(57) **CLAIM**

The ornamental design for an interphone, as shown and described.

DESCRIPTION

FIG. 1 is a front elevational view of an interphone illustrating my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front perspective view thereof;

FIG. 8 is a front elevational view of an interphone illustrating my new design;

FIG. 9 is a rear elevational view thereof;

FIG. 10 is a left side elevational view thereof;

FIG. 11 is a right side elevational view thereof;

FIG. 12 is a top plan view thereof;

FIG. 13 is a bottom plan view thereof; and,

FIG. 14 is a front perspective view thereof.

The broken lines in the drawings depict unclaimed subject matter only and form no part of the claimed design.
